UNITED STATES PATENT OFFICE.

CHARLES W. BOULTON, OF WALTHAM, MASSACHUSETTS.

CHAPLET.

Application filed May 24, 1922. Serial No. 563,453.

To all whom it may concern:

Be it known that I, CHARLES W. BOULTON, of Waltham, in the county of Middlesex and State of Massachusetts, have invented certain new and useful Improvements in Chaplets; and I do hereby declare the following to be a full, clear, and exact description of the invention, such as will enable others skilled in the art to which it appertains to 10 make and use the same.

My invention relates to chaplets such as are used in devotional exercises. The use of beads in the recitation of prayers had its origin before Christianity was known to the 15 world. The Psalms of David were in constant use as prayers among the Jews and primitive Christians adopted them, the pious as well as all who, as hermits or monks, sought religious perfection recited 20 the whole one hundred and fifty Psalms daily. Some there were who could not read and others who could not remember and these were allowed to recite the Lord's Prayer the same number of times and to 25 keep a record of these prayers they used belts or strings of beads. One of the most common forms of devotion in the present time is the Rosary instituted by Saint Dominic de Guzman the founder of the Order of 30 Friars. This devotional practice by many comprises in all fifteen decades divided into three parts, and to the five decades of each part are assigned the Mysteries of the Life 35 of Our Lord, these being the Joyful Mysteries, including the Visitation, the Nativ- 40 ity of Our Lord, His Presentation in the Temple, and His Finding in the Temple; the Sorrowful Mysteries which form the second part, and including His Bloody Sweat, His Scourging, His Crowning with Thorns, the carrying of His Cross and His Crucifixion; and lastly the Glorious Mysteries with the Resurrection of Our Lord, His Ascension, the Descent of the Holy 45 Ghost, His Assumption of His Blessed Mother into Heaven and her Coronation. The chaplet or pair of beads as it is commonly known comprises fifty beads arranged in series of ten and each series separated by 50 a single bead which is spaced from the series beads a greater distance than is each of such series to its fellow. The described arrangement is of endless form and at an appropriate point there is connected to the 55 chain a short length which terminates in a crucifix or cross, there being a bead next

adjacent the crucifix and spaced therefrom and in close arrangement three beads with an intervening space and a fourth bead which is itself spaced from the endless 60 chain. Upon the crucifix and the five beads on the depending length prayers introductory to the Rosary are said.

It is the object of my invention to provide a chaplet especially adapted to instruction. 65

In the drawings, Figure 1 shows a chaplet embodying my invention. Figure 2 shows one of the directional elements removed. Figure 3 is an enlargement of the 70 connecting piece.

According to custom some of the mysteries hereinbefore referred to are used for reflection on certain days of the week and within penitential seasons and others upon other days and other seasons and as an aid 75 to the novice I employ a number of flat elements which I call directional elements and upon each side of which I print or emboss or otherwise display an abbreviation indicating the information necessary to a correct telling of the beads. Upon the element 1 next adjacent the crucifix or cross I indicate that the Joyful Mysteries are to be reflected upon on Mondays and Thursdays, the Sorrowful Mysteries on Tuesdays and 80 Fridays, and the Glorious Mysteries on Sundays, Wednesdays and Saturdays. On the element 2 beyond the three beads A there is indicated the first of each of the three mysteries attending upon the first decade. 85 In order that the novice may proceed in an orderly way and reach the decades in proper sequence I provide the connecting bead 4 with an indicator 5 which is simply an elongation of the connecting beads and serves as 90 a finger to direct the user. The word "start" may be placed thereon if desired. Upon the faces of the piece 4 I may indicate the seasons of the year when certain of the mysteries are appropriate. It is to the 100 end of the indicator 5 that the chain upon which the beads are strung is fastened. The next spacing element 6 contains the abbreviations for the second of each of the mysteries, and this sequential arrangement 105 is continued upon the elements 7, 8, and 9.

It will be understood that I have provided a simple arrangement of directional elements in conjunction with a chaplet and one readily comprehensive, as well that the 110 means for indicating the direction for the user is easily understood.

I claim as my invention:

1. In a chaplet of five decades, a connecting piece between the first and last of said five decades having an indicator projecting from one portion of said connecting piece to direct the user in telling the beads, and a series of directional elements spacing said decades.
2. In a chaplet including a cross, a series of beads and introductory directional elements adjacent said beads, and five decades, a connecting piece to which said cross, series

of beads and introductory directional elements are attached, such beads forming the connection between the first and last of said five decades, an indicator projecting from one portion of said connecting piece in the direction of the first decade to direct the user in telling the beads, and a series of directional elements spacing said decades.

In testimony whereof I have signed this specification.

CHARLES W. BOULTON.
